UNITED STATES PATENT OFFICE.

GEORGE HARDEN, OF DETROIT, MICHIGAN.

DESIGN FOR A FRAME FOR BICYCLE-SEATS.

SPECIFICATION forming part of Design No. 24,438, dated June 25, 1895.

Application filed October 24, 1894. Serial No. 526,889. Term of patent 7 years.

To all whom it may concern:

Be it known that I, GEORGE HARDEN, a citizen of the United States, residing at Detroit, county of Wayne, State of Michigan, have invented a certain new and useful Design for Bicycle-Seat Frames; and I declare the following to be a full, clear, and exact description of the invention, such as will enable others skilled in the art to which it pertains to make and use the same, reference being had to the accompanying drawing, which forms a part of this specification.

The drawing shows in perspective the seat-frame.

The seat frame is composed essentially of a semicircular rear frame from the forward ends of which extend radially inward to the center the parts forming the front of the seat. From the center there also extends radially backward to the middle point of the arched rim, an arm uniting the center and the arched rim.

In the drawing the arched rear rim of the seat is shown by the part marked, A. The two front parts which extend radially from the center, are shown by the parts marked, B and C. These parts arch downward between the ends of the arch, A, and the middle and the

central part or pommel D, of the seat. The parts B and C also arch slightly backward from a straight radial line between the center and the ends of the rim A. The rearward extending part of the frame E also arches downward, and all of these parts are concave with the concavity downward. The rim A is somewhat angled in cross section as shown at a.

The prominent features of this seat frame consist in its extreme breadth compared with its length from front to rear, and in its dishing or dropping away from the line at which the saddle leather is supported; the support for the seat leather being along the line of the angle on the rim A and over the point of the pommel.

Having thus explained my invention, what I claim is—

The design for a bicycle seat shown and described.

In testimony whereof I sign this specification in the presence of two witnesses.

GEORGE HARDEN.
